E. B. WESTON

DISPLAY RACK ATTACHMENT

Filed Dec. 8, 1922

INVENTOR:

Edward B. Weston

BY Allen & Allen
ATTORNEYS.

UNITED STATES PATENT OFFICE.

EDWARD B. WESTON, OF DAYTON, OHIO.

DISPLAY-RACK ATTACHMENT.

Application filed December 8, 1922, Serial No. 605,716.

To all whom it may concern:

Be it known that I, EDWARD B. WESTON, a citizen of the United States, and a resident of Dayton, in the county of Montgomery and State of Ohio, have invented certain new and useful Improvements in Display-Rack Attachments, of which the following is a full, clear, and exact description, reference being had to the accompanying drawings forming part of this specification.

In recent years a great demand has arisen for display racks for the display of cartons and boxes for crackers, cakes and the like, in which provision is made for the display of the cartons either upright or at an angle, so that the cartons may be supported with their open glass-covered lids tilted in forward position. These cartons are not always of the same size, and where provision is made to bring the largest size of the boxes in front alignment, no provision has been made for boxes or cartons of smaller size when they must be mounted on the same shelf with full sized cartons.

It is extremely desirable and adds greatly to the neatness and attractiveness of the display that all the boxes shall have the same front alignment, and my invention consists of that certain attachment and construction for mounting same to attain the above desirable result.

The invention is particularly designed for use with metallic frame racks of the kind for example illustrated in my Patent No. 1,428,730, dated September 12, 1922, in which the rear support for the boxes comprises an open metallic frame. In this patent provision is made for swinging the entire rear frame forward to accommodate smaller sized boxes, but in this construction for any one shelf all of the cartons must be of the same size.

It is to obviate this difficulty and to provide for all the standard mixed sizes of cartons for any one or more shelves that my invention is directed.

It consists of that novel construction and arrangement to be hereinafter particularly pointed out and claimed, whereby this object is attained.

In the drawings,

Figure 1 is a perspective view of my attachment illustrated in position on one end of a metallic display shelf.

Figure 2 is a similar view showing the method of applying the device.

The attachment comprises an integral strip of metal with the ends bent preferably at right angles to form a front portion 1 and side supports 2, 2. These side supports are formed with slots 3, 3, at the outer ends and a plurality of L-shaped notches 4, 4, each notch of each pair being spaced at the same distance from the ends. The end slots are of a width to receive the back bar 5 of the shelf 6 and of sufficient depth to effectually embrace the back bar. The open portions of the L-shaped notches are of sufficient width to allow the back bar to enter the notch when the attachment is tipped and the slot portion is of sufficient depth to hold the attachment in place on the bar.

The distance from the base of the several slots to the front portion 1 is gauged to adjust the attachment for the various sizes of cartons so that by resting on the front portion, the boxes shall have their display portions all in alignment.

With this simple and effective device the user need have no concern as to sizes of cartons. With the smallest size the attachment is mounted on the back bar of the shelf in the end slots, and with intermediate sizes the attachment is mounted in the pair of L-shaped notches required to bring the supporting front of the attachment in position to maintain proper alignment for the display carton. Thus provision is made for filling the display shelf with properly aligned cartons irrespective of the order in which they may come.

As many sets of retaining slots for the attachment are provided as may be needed for the variation in standard sizes, and the user merely keeps on hand such number of attachments as may be required. It is, of course, immaterial whether the L-shaped notches open upwardly or downwardly, and, therefore, the attachment is fool-proof, and can be applied by anyone, no matter how ignorant he may be.

Having thus described my invention, what I claim as new and desire to secure by Letters Patent, is:

1. In a display rack, the combination with an open metallic shelf, of an attachment therefor, comprising an integral strip of metal made up of side arms and a front

connecting portion, with the side arms slotted at the ends in alignment for removably mounting same on the rear supporting member to change the point of support for the goods to be displayed on the shelf.

2. In a display rack, the combination with an open metallic shelf, of an attachment therefor, comprising an integral strip of metal made up of side arms and a front

connecting portion, with the side arms provided with L-shaped slots in alignment along the sides for removably and adjustably mounting same on the rear supporting member of the shelf to change the point of support for the goods to be displayed on the shelf for a plurality of positions.

EDWARD B. WESTON,
